UNITED STATES PATENT OFFICE

JAMES W. PEARCE, OF PHILADELPHIA, PENNSYLVANIA, ASSIGNOR TO NORTH WESTERN EXPANDED METAL COMPANY, OF CHICAGO, ILLINOIS, A CORPORATION OF ILLINOIS

EXPANDED-METAL LATH

Application filed January 5, 1929. Serial No. 330,519.

The invention relates to improvements in expanded metal lath and method of making the same and it consists in the matters herein-after described and more particularly pointed out in the appended claims.

The expanded metal lath with which my invention is particularly concerned is of that type formed by operating upon a previously slit sheet, to bend or deflect the strands to produce the open diamond mesh, the bent strands extending diagonally of the sheet in opposite directions and being connected at their intersections by bonds or bridges disposed in rows extending transversely of the sheet.

In this type of lath the strands are not placed under tension by stretching as in diamond mesh lath made by simultaneously slitting and stretching the strands so that it may be readily and advantageously made from very light gauge sheet metal. Lath of this kind heretofore generally accepted by the trade for the support of mortar and plaster coats in walls and ceilings, measures about 24" wide and 96" long and the slit sheet from which it is produced measures 8" wide by about 108" long. Such lath is furnished in different standard gauges and weights namely 24, 25, 26 and 27 gauge, which weighs about 3.4, 3.0, 2.5 and 2.2 pounds per square yard respectively, the most popular being the lightest gauge and weight, because greater yardage is secured for the same weight and purchase price. Such sheets were slit previous to expansion to provide about one hundred and thirty strands extending transversely of the sheet. Said bonds are about twelve hundredths of an inch wide and the strands are about six hundredths of an inch wide. The bonds are spaced about seven eights of an inch apart longitudinally of the sheet so that there are about one hundred and twenty four rows of such bonds and strands.

As such sheets are expanded to about twenty four inches wide which is about three times the original width, the transverse spacing of the bonds in each row will be about three eighths inches apart. The above mentioned lath represents the best form of open diamond mesh lath which the manufacturers

have heretofore made and which the trade has customarily accepted as the mortar and plaster support in walls and ceilings.

As a result of my study and research in this art, I have discovered that the lath above mentioned has a number of inherent objections. For example, with such lath it has been necessary for the plasterer to use a relatively dry mortar for the first coat. This requires the use of more mortar to properly cover the lath than is necessary with a mortar of a more fluid or mushy consistency. Such relatively dry mortar is also more difficult to apply so that the area of lath covered in a predetermined period of time is reduced. The natural inclination of the plasterer is to increase the fluidity of the mortar so that it may be more easily applied. Such practice however embodies other and probably more objectionable features. That is to say when this more fluid mortar is used a very considerable portion thereof will pass through the mesh under trowelling and form large keys or gobs at the rear of the lath, which slough off under their own weight. This not only results in a waste of mortar but brings forth another objectionable condition. It will be understood of course that it is desired to obtain a flat surface for such coat. However, when the large keys or gobs slough off they drop from the lath and produce a pulling action on the mortar on the front of the lath and cause the formation of depressions therein.

The main object of the present invention is to provide a lath of this kind which will have better mortar retaining qualities in that the metal of the lath is distributed in a different manner so as to form more retarding elements and smaller keys for the mortar, whereby a more fluid mortar may be employed and the sloughing off of the keys and resulting depressions in the surface of the mortar coat are reduced to a minimum if not entirely eliminated.

Another object of the invention is to provide a lath of this kind of standard weight per unit area wherein the usual number of open diamond mesh as well as the strands and bonds are materially increased.

Still another object of the invention is to

provide a lath of this kind which is practical to make from a previously slit sheet, upon machines at present in use without change.

These objects of the invention as well as others, together with the many advantages thereof will more fully appear as I proceed with my specification.

In the drawings:—

Fig. 1 is a diagrammatic view of a sheet of metal in substantially correct proportional area, from which the improved lath is formed after the sheet has been slit.

Fig. 2 is another diagrammatic view of the sheet in substantially correct proportional area after expansion and after the fish tail ends thereof have been trimmed off to make the sheet rectangular.

Fig. 3 is a view in elevation on a full size scale of one corner fragment of the sheet shown in Fig. 1 with the correct proportion of the slits therein to define the strands and bonds.

Fig. 4 is a view of the fragment shown in Fig. 3 after the same has been expanded.

Figs. 5 and 6 are detail sectional views on an enlarged scale as taken on the lines 5—5 and 6—6 respectively of Fig. 4.

In the present invention I provide a blank sheet of metal 1 of the desired gauge, weight and dimensions as heretofore employed which blank approximates eight inches in width and one hundred and eight inches in length. I operate upon said sheet in any convenient manner to produce therein transverse rows 35 of slits 2—2 extending lengthwise of the sheet. These rows of slits are so arranged that those in one row overlap and are disposed between those of adjacent rows to form transverse rows of bonds or bridges 3 and 4 respectively the endmost bonds in each alternate row being integral with the selvage portions 5—5 of the sheet.

The areas between the overlapping slits define the strands 6—6 which in the finished sheet extend diagonally of the sheet and are connected at their intersections by the integral bonds 3 and 4 respectively, the strands and bonds being disposed edgewise at an angle to the plane of the sheet.

In my improved lath the overlapping slits in one row are purposely spaced closer together than heretofore, thus making the strands 6—6 about five-hundredths of an inch in width instead of about six-hundredths as before mentioned. This produces about one hundred and fifty-six strands in each transverse row instead of one hundred and thirty as before mentioned. It is apparent that in a sheet of the same unit area there is thus provided in each transverse row an increased number of strands amounting to about one-fifth more strands than in a slit sheet wherein the strands are six-hundredths of an inch wide.

I purposely arrange the bonds closer to-

gether so that the length of the strands are reduced in proportion to that extent whereby the number of rows of slits lengthwise in the sheet is increased in number to about one hundred and forty-four. This represents an increase of about one sixth more rows than heretofore employed. By increasing the number of strands in each row about one-fifth and increasing the number of rows of strands about one-sixth an increase in strands and bonds is afforded in the sheet of the same unit area amounting to about one-third more than the number heretofore formed in such a sheet.

Such a slit sheet is then expanded in the usual manner, as by the expanding machines now in use and which can be employed for this purpose without change except readjustment changes. When such a sheet is expanded and trimmed in the usual manner it will have the same unit area as before mentioned and approximating twenty-four inches by ninety-six inches.

It is pointed out that in the finished expanded sheet as shown in Figs. 4, 5 and 6 the bonds in each alternate transverse row extend edgewise and perpendicularly to the plane of the sheet while the bonds in each intermediate row are inclined and extend edgewise at an angle of about 60° to the plane of the sheet. This peculiar difference in angularity is due to certain characteristics in the sheet itself after being slit as for instance with a particular type of slitting mechanism which forms no part of the present invention.

As is well known in sheet lath of this kind, the stiffness of the sheet as represented by the tendency to flex under its own weight in applying it in place upon the usual furring strips as well as its action in remaining flat when so applied, is due to the number of bonds provided and the relative angularity of such bonds to the plane of the sheet.

With my improved lath, with the same weight per unit area of sheet, the metal is distributed in a manner different from that heretofore recognized as the only possible way. Therefore, a greater number of bonds is provided in my improved sheet with the bonds in one-half of the rows disposed edgewise and perpendicularly to the plane of the sheet and with the other half disposed edgewise at the sixty degree angle before mentioned so that the stiffness of the sheet is increased. Such a sheet of course handles better in applying the same to furring strips and like supporting members and at the same time provides a more rigid structure when embedded in wall material.

In the improved lath the diamond mesh are smaller in area but greater in number and a greater number of mortar retarding elements as defined by the strands and bonds are presented. Such a lath better receives the mortar which may be used in that mushy

consistency desired by the plasterers so that the same is better adapted for faster application and of a less depth or thickness than heretofore possible.

5 Again with an increased number of smaller mesh, together with an increased number of retarding elements less motar is consumed in forming the keys in the rear side of the lath and the keys are smaller and lighter in weight so that they do not slough off. Thus waste is reduced to a minimum as well as the objectionable pulling action on those portions of the mortar in line with the mesh or openings.

10 The thin coat of mortar made practical by my improved lath is indeed desired by the plasterers because it is more economical and easier applied and it dries or seasons quicker so that less shifting of scaffolding between 15 coats is necessary. Actual tests disclose the mortar and plaster saving qualities of my improved lath.

20 It is pointed out that although the dimensions of the strands and bonds as well as the open diamond mesh is reduced to a certain extent, the number thereof is increased about a third which indeed more than compensates for the reduction mentioned so far as stiffness of the finished lath is concerned.

25 With the increased number of strands and bonds the lath is better distributed in the wall material which it more effectively retains and reinforces.

30 While in describing the invention I have referred in detail to certain dimensions, details of construction as well as form and arrangement of the parts thereof, the same is to be considered purely as illustrative so that I do not wish to be limited thereto except as 35 may be pointed out specifically in the appended claims.

40 I claim as my invention:

45 1. An improved mortar receiving and holding, expanded sheet metal diamond mesh lath, the strands of which are approximately .05 inches in width and a number of strands in each longitudinal row of meshes being approximately 144 in a lath 96 inches along after the metal has been expanded.

50 2. An improved mortar receiving and holding, expanded sheet metal diamond shape lath expanded transversely at the rate of three to one, having bonds connecting the strands, the strands of which are approximately five-hundredths inches in width and the length of a strand on two sides of the diamond mesh being from center to center of the bonds approximately three fourths of an inch.

55 3. An improved mortar receiving and holding, expanded sheet metal diamond shape lath expanded transversely at the rate of three to one, having bonds connecting the strands, the strands of which are approximately five-hundredths inches in width and

the length of a strand on two sides of the diamond mesh being approximately three-fourths of an inch, alternate bonds being in a plane at right angles to the plane of the lath while the other alternate bonds are at an acute angle to said plane.

60 In testimony whereof, I have hereunto set my hand, this 3rd day of Jan., 1929.

JAMES W. PEARCE.
